UNITED STATES PATENT OFFICE.

JACQUES SCHNEIDER, OF SOLOTHURN, ERNST HURLIMANN, OF ZUCHWIL, AND
FREDERIC BILLON, OF SOLOTHURN, SWITZERLAND, ASSIGNORS TO THE FIRM
"SCINTILLA," OF SOLOTHURN, SWITZERLAND.

ELECTRIC IGNITION DYNAMO.

1,411,304.

Specification of Letters Patent. Patented Apr. 4, 1922.

Application filed August 22, 1919. Serial No. 319,232.

To all whom it may concern:

Be it known that we, JACQUES SCHNEIDER, a citizen of the Swiss Republic, residing at Solothurn, Switzerland, ERNST HURLIMANN, 5 a citizen of the Swiss Republic, residing at Zuchwil, Canton of Solothurn, Switzerland, and FREDERIC BILLON, a citizen of the Swiss Republic, residing at Solothurn, Switzerland, have invented certain new and useful 10 Improvements Relating to Electric Ignition Dynamos, of which the following is a specification.

This invention has for its object to provide an improved means of attaching the lever for varying the point of ignition in ignition dynamos for internal combustion engines in which the point of ignition is varied by rotating the fixed part relatively to the rotary part of the interrupter. Since 15 the lever for varying the point of ignition has to be arranged in various directions in order to be conveniently accessible according to the manner in which the ignition dynamo is built in the mechanism provided 20 with it, the hub of the said lever is provided according to the present invention with projections or recesses adapted to fit respectively in recesses or on projections of suitable form and size on the adjustable portion 25 of the interrupter mechanism; the projections or recesses at least on one of the two parts being provided in number and arrangement to correspond to the various directions of the lever.

30 The accompanying drawings illustrate some constructional examples of this invention.

Figure 1 shows a longitudinal section through the device of an embodiment of the 35 invention.

Figure 2 is a section on line X—X of Figure 1, in which notches are provided in the edge of the coupling disc.

Figure 3 is an end view with parts omitted for clearness.

As shown, the cover *f* of the adjusting lever *a* (for varying the point of ignition) constitutes also the cover of the aperture in the machine casing *b*, through which the 50 supporting piece *c* surrounding the cam plate *g*, can be removed together with the interrupter parts *d* and *e*. The cover *f*, which can be adjusted concentrically by

means of the lever *a* together with the supporting part *c* in opposition to the spring *r*, has its projecting edge *h* guided concentrically in an annular groove *i* of the machine casing *b*, and is connected to the interrupter-supporting part *c* by means of a screw *k* 60 which is situated in the central axis and which engages in a concentric boss *p* on the cover *f*. This connection can, according to this invention, be established in different relative positions of the two parts according 65 to the requirements of each particular case for which a constructive solution is given in Fig. 2 which is a section approximately on the line X—X of Fig. 1.

As shown in Figs. 1 and 2, the cover hub *f* 70 is formed on its inner side with two projections *m*. On the interrupter-supporting piece *c* there is screwed a disc *n* having twelve notches *o* in any two diametrically opposite ones of which the two projections 75 *m* can be engaged. The parts *c* and *f* are thus rigidly coupled together by a sort of claw clutch, and the lever *a* can be attached to the machine in twelve different positions.

Figure 3 shows an end view of Figure 1 80 with the parts *f*, *s* and *n* removed, thus showing clearly the attachment of the spring *r* to the carrying piece *c* and the fixing ring *t*. This fixing ring allows the interrupter to be removed bodily from the machine in an 85 axial direction when the bayonet notches *v* and slots *w* face each other; but when in the working position the spring *r* forces the fixing ring round until its extension *t* abuts against the shoulder *u* of the casing *b* and 90 the bayonet device is then locked.

Further constructional forms of the invention are obviously possible.

What we claim is:—

1. A means for attaching an adjustable 95 lever on a supporting piece surrounding the cam plate for varying the point of ignition caused by the interrupter, in electric ignition dynamos, comprising a circular cover, concentrically pivoted, with a depending flange, 100 with projections, and a central boss on one face of same, and a projecting lever extending beyond the periphery of the cover for rotating same by hand, in combination with a coupling disc, having openings therein, 105 on the edge thereof, which correspond with and engage projections on said cover to vary

the point of ignition when such cover is operated in the desired direction, substantially as described.

2. Means for attaching an adjustable lever on a supporting piece surrounding the cam plate, for varying the point of ignition caused by the interrupter of electric ignition dynamos, comprising a circular cover concentrically pivoted, having a depending flange with projections and central boss on one face of same, and a projecting lever ex-

tending beyond the periphery of the cover for rotating same by hand in combination with a screw engaging the central boss of cover for connecting it to the interrupter supporting part, substantially as described. 15

In testimony whereof we have signed our names to this specification.

JACQUES SCHNEIDER.
ERNST HURLIMANN.
FREDERIC BILLON.
